UNITED STATES PATENT OFFICE.

WILLIAM J. NETHERCOTT, OF KERROBERT, SASKATCHEWAN, CANADA.

ASH-SIFTER.

1,156,923.

Specification of Letters Patent. Patented Oct. 19, 1915.

Application filed August 5, 1913. Serial No. 783,124.

To all whom it may concern:

Be it known that I, WILLIAM J. NETHERCOTT, a subject of the King of Great Britain, residing at Kerrobert, in the Province of Saskatchewan and Dominion of Canada, have invented new and useful Improvements in Ash-Sifters, of which the following is a specification.

This invention relates to an ash ejector or device for disposing of the ashes produced by a furnace in a basement of a building, the primary object being to provide a device of this character which includes a receptacle into which the ashes may be poured without causing a great amount of dust to rise therefrom, together with readily operable means for sifting the ashes and conveying the fine portions of the same out of the basement to a receptacle disposed upon the exterior of the building.

A further object of the invention is to provide a device of this nature, which is simply constructed and compact so as to be cheap in the cost of manufacture and installation, and adapted to occupy a minimum amount of space.

The invention consists in the features of construction, combination, and arrangement of parts, hereinafter fully described and claimed, reference being had to the accompanying drawings, in which:

Figure 1 is a vertical longitudinal sectional view; Fig. 2 is a side elevation of a modified form of the device; Fig. 3 is a front elevation of the same; and, Fig. 4 is a longitudinal vertical sectional view taken therethrough.

In the drawings, the numeral 1 designates the receptacle or ash box which is mounted upon the legs 2. The bottom wall of the receptacle includes the side portions 4 which converge inwardly toward an upwardly and inwardly inclined conveyer tube 5. A spiral conveyer 10 is positioned within the tube 5 with the ends of its shaft 11 journaled in the upper and lower end walls 12 and 13 of the tube, respectively. A band wheel 14 is secured to the protruding lower end of the shaft 11 and is connected with a second band wheel 15, which is secured to a horizontal shaft 16 rotatably mounted in the front wall 17 of the receptacle 1 adjacent to its upper edge, by means of a band 18. Owing to the inclination of the axes of the band wheels 14 and 15 with respect to each other, two pulley wheels 19 and 20 are journaled

upon a transversely extending, horizontal shaft 21, which latter is mounted upon the front wall 17 adjacent to the lower edge thereof, these pulley wheels being engaged with the side stretches of the band 18 immediately above the band wheel 14 so as to cause the said band to move in two inclined planes. A crank 22 having a handle 23 is secured to the shaft 16 so as to afford means by which the spiral conveyer may be operated manually. It is to be understood that other means for connecting the operating crank shaft with the conveyer shaft may be employed without departing from the spirit of the invention, such as sprocket wheels and chain, beveled gears and shafts, or the like, and it is considered unnecessary to show such specific embodiments of the invention in the drawings.

The top wall of the conveyer tube 5 is cut away at its lower end as at 24 so as to afford a mouth for the reception of ashes falling into the receptacle 1. This receptacle is provided in each side wall 25 thereof and adjacent to its upper edge with an opening 26 in which a hinged closure 27 is suspended. Each closure or door 27 is adapted to be swung inwardly when it is desired to pour ashes through the corresponding side opening of the receptacle into the interior thereof, and serves to prevent the dust rising within the receptacle from gaining exit through the said opening, it being understood that the top wall 28 of the receptacle 90 is completely closed. A foraminous sifter screen 29 is disposed horizontally within the receptacle 1 at a suitable distance below the openings 26. By the use of this screen, large cinders and lumps of unburned coal will be 95 collected and may be withdrawn for further use as fuel.

In using the device, just described, the ashes are poured through the side openings 26 in the receptacle 1 so that the finely divided portions thereof will pass through the sifter screen and through the mouth 24 of the conveyer tube into contact with the spiral conveyer 10. Then the handle 23 is grasped and the crank is operated so as to cause rotation of the conveyer in the proper direction, whereupon the ashes will be forced upwardly and outwardly through the tube 5.

In the remaining figures of drawing, a modified form of the device is shown, where in a shaker screen 29a is pivoted at its rear edge as at 30 to the front edge of a shelf

31 provided within the receptacle of the device. This screen is inclined upwardly and forwardly from its pivoted edge and has an outwardly projecting arm 32 formed 5 medially on its front edge for movement through a vertical slot 33 provided in the front wall of the receptacle. A vertically movable connecting rod 34 has its lower end pivotally connected at 35 to the protruding 10 extremity of the arm 32 and has its upper end pivotally connected to a crank pin 36 mounted eccentrically on the outer face of a gear wheel 37 which latter is connected with a horizontally disposed rotatable shaft 38 15 journaled in the front wall of the receptacle beneath the crank shaft previously described. This gear wheel 37 is in mesh with a larger gear wheel 39 attached to the said crank shaft. An opening 40 having 20 a suitable closure 41 is provided in one of the side walls of the receptacle directly above the shelf 31 for a purpose to be described fully hereinafter. In using this modified form of the device, the ashes are introduced in the usual manner through the side openings in the receptacle. Then, the crank handle is operated so as to cause the conveyer to be set into operation. At the same time, the inclined shaker screen will be 25 vibrated rapidly by the mechanism just described so as to sift the ashes more thoroughly. The large cinders and lumps of unburned coal that may be deposited upon the screen will gravitate rearwardly onto the shelf 31 from which they may be removed 30 by the insertion of a shovel through the opening 40 when the closure or door 41 has been opened. This removal of the large pieces of material should not take place until after the separating operation has been 35 completed and the fine dust within the receptacle has been allowed to settle.

From the foregoing description, taken in connection with the accompanying drawings, it should be apparent that I have provided 45 a simply constructed and compact ash ejector which may be cheaply and conveniently installed and which will be highly efficient in operation. I desire to have it understood, however, that I do not necessarily limit 50 myself to the exact details of construction, with particular reference to the manner in which the crank shaft of the device is connected with the spiral conveyer, or the specific means for operating the shaker screen, 55 but that I may resort to minor changes therein, such as fall within the scope of the appended claim, if found necessary in practice.

Having thus described my invention what 60 I claim is:

A device of the class described comprising a receptacle, the said receptacle having its bottom wall inclined downwardly and forwardly and provided at its lower edge with 65 a discharge opening, the side walls of the said receptacle having their lower portions inclined downwardly and inwardly toward the discharge opening, a sifter screen mounted within the receptacle above the inclined 70 portions of the side walls thereof, the said screen being adapted to be inclined downwardly and rearwardly and having its rear edge spaced from the rear wall of the receptacle, and a horizontally arranged shelf 75 mounted in the receptacle between the rear wall of the same and the rear edge of the screen.

In testimony whereof I affix my signature in presence of two witnesses.

WILLIAM J. NETHERCOTT.
